LIQUID DISPERSING APPARATUS

Robert J. Jauch and Christian W. Kuckeberg, Fort Wayne, Ind., assignors to General Development Company, Fort Wayne, Ind., a partnership

Application April 23, 1953, Serial No. 350,593

11 Claims. (Cl. 299—63)

This invention relates to dispersing apparatus, and more particularly to liquid dispersing apparatus. The apparatus is especially useful in dispersing insecticides, herbicides, and other toxic materials which are in a liquid state or are carried in a liquid solution, but may be used to disperse any liquid wherein it is desired to provide a fine spray or mist.

An object of the invention is to provide liquid dispersing apparatus wherein selective control over the quantity of liquid dispersed into an air stream in a given amount of time is provided. Another object of the invention is the provision of adjustable valve means in liquid dispersing apparatus wherein a metered amount of liquid is permitted to flow onto a rotatable distribution plate that distributes the liquid as tiny droplets into an air stream in which the liquid droplets are dispersed as a fine spray or mist. Still another object is to provide a fan and direction plate arrangement for maintaining an air stream for picking up and distributing the liquid droplets and in which an air layer or sheath is maintained over the surface of the direction member that is effective to prevent the impinging of the liquid droplets thereon, with the result that coalescence of the droplets that is usually caused by impinging of droplets on a member is obviated.

A further object of the invention is in providing liquid dispersing apparatus having a meter valve, fan and direction member for providing an air stream, and distributor plate for transferring the liquid discharged from the valve as fine droplets into the air stream, and in which all of the members rotate together during the operation of the apparatus. Still a further object is to provide liquid dispersing apparatus having the elements set out and in which the distributor plate is substantially covered to maintain a relatively quiescent air zone thereabout. Yet a further object is to provide in liquid dispersing apparatus a metering valve interposed in the liquid flow path from a reservoir to a rotatable distributor plate; the valve having a stationary and movable portion with lapped faces, each portion providing flow passages therethrough adapted to be brought into register to control the amount of liquid delivered to the distribution plate. Additional objects and advantages will appear as the specification proceeds.

An embodiment of the invention is illustrated in the accompanying drawing, in which—

Figure 1 is a top plan view of the dispersing apparatus; Fig. 2 is a vertical sectional view partly in elevation and taken on the line 2—2 of Fig. 1; Fig. 3 is a transverse sectional view taken on the line 3—3 of Fig. 2; Fig. 4 is a transverse sectional view taken on the line 4—4 of Fig. 2; Fig. 5 is a perspective view of the valve selector member; Fig. 6 is a top plan view of a modified apparatus; Fig. 7 is a broken vertical sectional view of the modification taken on the line 7—7 of Fig. 6; Fig. 8 is a top plan view of the valve selector metering plate; and Fig. 9 is a top plan view of the valve plate.

The liquid dispersing apparatus comprises a reservoir

A, motor assembly B, a dispersing head C, and a bail D, carried by the motor assembly B and providing a handle by which the apparatus may be carried and that facilitates ready portability.

- 5 The reservoir A is formed by a casing 10 providing a chamber 11 therein. The bottom wall of the casing 10 provides a support for the apparatus and may be placed upon any substantially horizontal surface. An opening is provided in the casing 10 and the opening is equipped 10 with a closure plug 12 that may be provided with an opening therethrough so that the interior of the reservoir is at atmospheric pressure. The top wall of the casing 10 has an enlarged opening therethrough and a plate 13 is received upon the top wall of the casing and provides a closure for the enlarged opening therethrough. The plate 13 may be rigidly secured to the casing 10 by cap screws 14 and if desired a suitable gasket may be interposed between the plate and the top wall of the casing to provide a seal therebetween.
- 15 20 Rigidly carried by the support plate 13 is a motor housing 15 that encloses an electric motor therein that is conventional and is not shown. The motor within the housing 15 has a rotor supported in a bearing 16 carried by a depending hub member 17 rigidly secured to the plate 13. Any means for securing the depending hub 17 to the plate 13 may be employed and if desired, the hub may be formed integrally with the plate. The motor is equipped with a hollow tube or shaft 18 that is carried by the rotor of the motor and is rotatively driven when 25 the motor is actuated. The upper end of the hollow tube or shaft 18 extends above the motor housing 15 and at its lower end it communicates with a bushing or connector member 19 carried in the bearing 16 and receiving a depending pickup tube 20 in the lower end 30 thereof. An enlarged tube 21 encloses the pickup tube 20 and provides a guard therefor. The pickup tube 20 and the guard tube 21 enclosing the same extend downwardly into the interior of the reservoir and below the level of the liquid contained therein.
- 35 40 The upper end of the hollow motor shaft 18 is threaded externally and threadedly receives thereon a bushing 22. The bushing 22 carries and has secured thereto a distributor plate 23 equipped with a plurality of spaced-apart vanes or fan blades 24. The distributor plate 23 should 45 be rigidly secured to the bushing 22 and any means to accomplish such a mounting may be employed. For example, the depending hub portion 25 of the distributor plate 23 may be equipped with a central opening therethrough that receives the upper end of the bushing 22 and the two members may be sweated together. The plate member 23 is annular and provides a smooth upper surface that is substantially horizontally oriented. A dish shaped director guard 27, having an upwardly and 50 outwardly inclined wall portion 28 and a downwardly and inwardly inclined wall portion 29, is carried by the distributor plate 23 and is secured thereto by a plurality of screws 30. The direction plate 27 is equipped centrally with an enlarged annular opening 31 therethrough that provides a throat about the motor shaft and is operative with the vanes 24 to draw air therethrough and 55 to discharge it upwardly along the inner surface of the direction member 27.
- 55 60 65 70 The upper surface of the distributor plate 23 is provided with an annular recess 32 that has mounted therein a lower valve plate 33. A sealing gasket 34, which may be a rubber O ring, is interposed between the plate 23 and valve plate 33 to provide a seal therebetween. Operatively arranged with the lower valve plate 33 is a valve selector member 35 having a horizontal wall portion 36 equipped with a depending annular contact member 37 that slidably engages the upper surface of the valve plate 33. A stem 38 is formed integrally with the horizontal

75 80 85 90 95 100

portion 36 and extends upwardly therefrom and is equipped with a slot 39 that is adapted to receive the point of a screw driver so that the selector member may be turned relative to the valve plate 33. A globular closure member 40 receives the upper end of the stem 38 and has a downwardly extending central portion supported upon the outer peripheral surface of the valve plate 33. The member 40 has outwardly and downwardly extending wall portions 41 that substantially enclose or cover the distributor plate 23 while being spaced therefrom as at 42 to permit the flow of liquid between the plate 23 and the wall portions 41 of the closure. A helical spring 43 is mounted about the stem 38 and seats upon the horizontal portion 36 of the valve selector 35 and upon the upper wall of the closure member 40 and normally biases the selector member downwardly and into engagement with the upper surface of the lower valve plate 33. A plurality of studs 44 extend through aligned bores within the closure member 40, valve plate 33, and distributor plate 23, and secure all three of these members together. It is apparent that the entire head C of the dispersing apparatus rotates upon actuation of the motor.

As will be seen best by reference to Fig. 4, the valve plate 33 is provided with three spaced-apart openings 45 therethrough that are adapted to receive the studs 44. The plate 33 is also provided with a plurality of L-shaped flow passages 46 therethrough that have a horizontally-extending portion 47, and a vertical portion 48 in open communication with the horizontal passage 47 and with the upper surface of the valve plate 33 (Fig. 2). The valve plate 33 and the selector member 35 provide therebetween a valve chamber 49 and the L-shaped flow passages 46 communicate with the valve chamber 49 through metering orifices 50 in the contact portion 37 of the selector member 35. Control over the quantity of liquid flowing through the valve chamber 49 and on to the distributor plate 23 is provided by selectively registering the desired metering orifices 50 with the vertical passage portions 33 and the L-shaped passages 46. The metering adjustment of the valve selector 35 is accomplished by rotation of the selector member within the limits provided by the recesses between the upwardly-extending abutments 51 carried on the upper surface and the horizontal plate 36 of the selector member. Stop pin 51a carried by the closure member 40 cooperates with the abutments 51 and thereby limits the permissible rotation of the selector member 35. As is seen in Fig. 3, the selector member 35 may be provided with an additional series of metering orifices 52 diametrically opposite the metering orifices 50. The metering orifices 52 are normally inoperative but may be brought into operative arrangement with the passages 46 by rotating the selector member 35 180 degrees relative to the valve plate 33. Such rotation cannot be accomplished without disassembling the specific apparatus illustrated in Fig. 2.

Operation

In operation the reservoir 10 is filled with an appropriate liquid solution that may be an insecticide, herbicide, or other toxic material that is suitable for the particular use for which the apparatus will be employed. The motor within the motor housing 15 will be connected to a suitable source of power and upon actuation of the motor through a switching arrangement of any desired form that may be incorporated with the motor, the motor is actuated and the dispersing head C will be rotatively driven thereby. Rotation of the head C will create an air stream that flows upwardly about the throat of the motor and through the central opening 31 in the direction member 27. The air stream will flow upwardly within the direction member 47 and will provide a sheath or layer of air over the inner surface thereof.

Rotation of the head C will also create a relatively low pressure zone within the space provided between the

closure member 40 and the distributor plate 23 and the atmospheric pressure within the reservoir will force the liquid therein upwardly and through the hollow motor shaft 18 and into the valve chamber 49. From the valve chamber 49 the liquid will flow through the metering orifices 50 that are in register with the L-shaped passages 46 in the lower valve plate 33 and outwardly therefrom and on to the upper surface of the distributor plate 23. The liquid will travel outwardly over the upper surface of the distributor plate 23 as very fine droplets or liquid particles and will be thrown outwardly from between the plate 23 and closure member 40 and into the air stream that is provided about the periphery of the distributor plate 23. The air stream will carry the fine droplets upwardly and outwardly where they will be distributed as a fine spray or mist by the air stream.

In actual operation of the apparatus the direction plate 27 is covered on the inner surface thereof by a layer or film of air and the tiny liquid droplets discharged from the distributor plate 23 do not impinge upon the direction plate or guard 27, but are carried upwardly by the air stream and do not contact the direction plate. The direction member 27 remains dry during the operation of the apparatus and there is no wastage of the liquid through collection of the liquid thereon. Similarly since the liquid particles do not impinge upon the direction plate 27 there is no coalescence of the liquid particles due to any impinging action. This result is not achieved if the direction member 27 is not imperforate and it is then desirable to provide a direction plate that is imperforate throughout its entire area.

Many of the insecticides, etc. used in dispersing apparatus are quite expensive and it is therefore desirable to disperse only the amount of liquid that is necessary to accomplish a given result. Metering valve means is provided therefore so that the amount of liquid reaching the distributor plate 23 may be accurately controlled. This result is achieved by providing a plurality of metering orifices 50 that vary in size. Therefore, by bringing selectively the required orifices 50 into communication with the L shaped passages 46 only the amount of liquid that can flow through the selected orifice will be delivered to the distributor plate. To permit ready adjustment of the orifices it is preferred that the upper surface of the selector stem 38 be equipped with an arrow or pointer as is indicated in Fig. 1 and appropriate indicia may be stamped upon the upper surface of the closure member 40 and aligning the arrow with the proper marking upon the closure member will provide the desired flow rate. Appropriately the markings upon the closure member may be calibrated in ounces of flow by unit of time, such as minutes, hours, etc.

It is apparent by referring to Fig. 2 that the closure member 40 covers substantially the entire upper surface of the distributor plate 23. This arrangement results in a relatively quiet zone of air about the distributor plate and there is little tendency then toward turbulence and coalescence of the tiny liquid particles will not be caused by air turbulence.

In the modification illustrated in Figs. 6 through 9, the apparatus is substantially the same as that heretofore described. The specific metering valve arrangement, however, has been modified slightly and includes a lower valve plate 55 threadedly carried on the upper end of the hollow motor shaft 18. The valve plate 55 is equipped with a vertical flow passage 56 therethrough that communicates through an outlet port 57 with the upper surface of the distributor plate 23'. The single flow passage 56 is provided and threaded apertures about the periphery of the valve plate receive studs 58 that hold the closure member 40' upon the valve plate 55.

In the modification the valve selector member 59 is changed slightly and is formed in two portions, an upper selector portion 60 and a lower plate portion 61 having an upwardly-extending annular wall 62a that is rigidly

secured to the upper selector member 60 by sweating or other suitable means. A valve chamber 62 is provided by the metering valve members and a plurality of metering orifices 63 in the member 61 communicate with the valve chamber 62 and selectively register with the flow passage 56 within the lower valve member 55.

As is seen best in Fig. 8, six orifices 63 are provided about the member 61 and these are spaced apart by 60 degrees. Each of the orifices is of a definite size and therefore by bringing the required orifices 63 into register with the flow passage 56, the desired flow rate may be provided. A coil spring 64 urges the selector member 59 against the lower valve plate 55. The selector member 59 and upper surface of the closure member 40' may be equipped with cooperating indicia so that the desired flow rate is readily provided by aligning the indicia in the required manner. Fig. 6 shows such indicia.

It has been found in both the embodiments illustrated in Figs. 1 through 5 and in Figs. 6 through 9 that the inertia of the valve members, etc., does not cause slipping of the upper valve member relative to the lower valve plate upon starting of the motor if the biasing force of the spring 43 or 64 is about 20 to 25 pounds. This force is not, however, sufficient to cause difficulty in selectively positioning the selector member 35 or 59 to provide the desired flow rate.

While in the foregoing specification embodiments of the invention have been set out in considerable detail for the purpose of illustration, it will be apparent to those skilled in the art that considerable changes may be made in these details without departing from the spirit of the invention.

We claim:

1. In apparatus for dispersing liquids, a reservoir for the liquids, a distributor member equipped with a plurality of vanes, a direction member carried by said distributor member and having walls diverging upwardly and outwardly therefrom and being arranged with said vanes to provide an upwardly oriented air stream about said distributor member and between it and the direction member, means for providing a flow of liquid from said reservoir to said distributor member when said apparatus is in operation, and adjustable valve means for metering the flow of liquid from said reservoir to said distributor member and being interposed in the path of flow of liquid from said reservoir to said distributor member.

2. In dispersing apparatus, a reservoir adapted to receive liquid therein, a tube communicating at one end with said reservoir and adapted to be rotatively driven, motor means arranged with said tube for rotatively driving the same, a distributor plate rigidly carried by said tube, a valve plate carried by said distributor plate and being equipped with a plurality of spaced-apart flow passage therethrough communicating with the surface of said distributor plate, and a valve selector member operatively arranged with said valve plate and having at least two spaced-apart metering orifices therein communicating with said tube and adapted to communicate with said flow passages, said selector member being movable relative to said valve plate to selectively register one or the other of the metering orifices in said selector member with one of said flow passages or to simultaneously register each of said metering orifices with one of said flow passages.

3. In dispersing apparatus, a reservoir, a motor, an elongated tube communicating with said reservoir and adapted to be rotatively driven by said motor, a distributor plate rigidly carried by said tube, a valve plate carried by said distributor plate, a selector member operatively arranged with said valve plate, and a fan for providing an air stream about said distributor plate, said valve plate having at least one flow port therethrough communicating with said distributor plate, and said selector member having at least two metering orifices of different sizes communicating with said tube and adapted to communicate selectively with said flow port, said selector member being

movable relative to said valve plate to selectively register said metering orifices with said flow port.

4. In liquid dispersing apparatus, a reservoir, a motor mounted upon such reservoir and being equipped with a tubular shaft communicating with said reservoir, a vane equipped distributor plate rigidly carried by said tube, a direction member carried by said distributor plate and arranged with said vanes to provide an upwardly oriented air stream thereabout, a closure member substantially covering the upper surface of said distributor plate and providing a relatively large, substantially closed chamber thereabout, a valve plate carried by said distributor plate and having at least one outlet passage communicating with the upper surface of said distributor plate, and a valve selector member equipped with a plurality of spaced-apart metering orifices of different sizes communicating with said tube and adapted to selectively communicate with said outlet passage, said valve selector member being movable relative to said valve plate to selectively register 20 said metering orifices with said outlet passage.

5. In apparatus for dispersing liquids and having a flow passage communicating with a reservoir and with a dispersing means for carrying liquid therebetween, said dispersing means comprising a distributor member for providing outwardly traveling droplets and an air stream, a direction member for guiding said air stream upwardly and outwardly in the path of travel of said droplets adjustable valve means for metering the flow of liquid through said passage comprising a valve plate and a valve selector providing together a valve chamber communicating with said passage, said valve selector having at least two openings of different size therethrough communicating with said chamber, said valve plate having at least one flow port therethrough adapted to communicate with said openings, at least one of said valve plate and valve selector being movable relative to the other to provide selective registration of the openings and port to control the flow of liquid through said passage.

6. The structure of claim 5 in which said valve plate is equipped with a plurality of flow ports therethrough communicating with said dispersing means, said flow ports and said openings being interrelated in an arrangement such that selective registration of one or more of the openings with one or more of the ports is afforded.

7. In apparatus for dispersing liquids, a reservoir for the liquids, a distributor member, means for rotating said distributor member upon actuation of said apparatus, means for providing a flow of liquid from said reservoir to said distributor member when said apparatus is in operation, said distributor member being positioned for discharging droplets outwardly along lines radiating from the rotational axis thereof and being equipped with blades for providing an upwardly oriented air stream, and a direction member for guiding said air stream upwardly and outwardly in the path of travel of said droplets, and adjustable valve means for metering the flow of liquid from said reservoir to said distributor member comprising a valve member provided with at least one flow passage therein communicating with said distributor member, and a valve selector member having a plurality of spaced-apart metering orifices interposed in the path of flow of liquid from said reservoir to said distributor member and being adapted to register selectively with each of said flow passages, said selector member being movable relative to said valve member to provide selective registration of the orifices and each of the flow passages.

8. Apparatus for dispersing liquids, a reservoir for the liquids, a distributor member, means for rotating said distributor member upon actuation of said apparatus, means for providing a flow of liquid from said reservoir to said distributor member when said apparatus is in operation, said distributor member being positioned for discharging droplets outwardly along lines radiating from the rotational axis thereof and being equipped with blades for providing an upwardly oriented air stream, and a direction member for guiding said air stream upwardly

and outwardly in the path of travel of said droplets, and adjustable valve means for metering the flow of liquid from said reservoir to said distributor member comprising a valve member carried by said distributor member and being provided with at least one flow passage therein communicating with the distribution surface of said distributor member, and a valve selector member having a plurality of spaced-apart metering orifices interposed in the path of flow of liquid from said reservoir to said distributor member and being adapted to register with each of said flow passages, said selector member being rotatable relative to said valve member and slidably mounted thereon, said selector member being equipped with means to rotate the same relative to said valve member to selectively register said orifices and each of the flow passages.

9. The structure of claim 7 in which said valve member is equipped with a plurality of flow passages extending radially outwardly toward the periphery of the member and in spaced-apart relation, each of said flow passages communicating at the outlet end thereof with the distribution surface of said distributor member and at the other end thereof with the upper surface of the valve member, said selector member being equipped with a plurality of orifices that communicate with the face thereof that slidably engages said valve member.

10. The structure of claim 5 in which said valve plate is equipped with a single L-shaped flow passage communicating at one end with the distribution surface of said distributor member and at the other end with the upper surface of the valve plate, said selector member being equipped with a plurality of spaced-apart orifices of different cross-sectional area adapted to communicate at one end with said L-shaped flow passage, and rotation of said selector member is adapted to provide selective

registration of said orifices with said L-shaped flow passage.

11. In apparatus for dispersing liquids, a reservoir for the liquids, a distributor member equipped with a plurality of fan blades, a direction member carried by said distributor member and arranged with said blades for providing an air stream about said distributor member, a closure member substantially enclosing the distribution surface of said distributor member and providing a chamber thereabove, means for rotating said distributor member upon actuation of said apparatus, means for providing a flow of liquid from said reservoir to said distributor member when said apparatus is in operation, and adjustable valve means for metering the flow of liquid from said reservoir to said distributor member comprising a valve member provided with at least one flow passage therein communicating with said distributor member, and a valve selector member having a plurality of spaced-apart metering orifices interposed in the path of flow of liquid from said reservoir to said distributor member and adapted to register with each of said flow passages, said selector member being movable relative to said valve member to provide selective registration of the orifices and each of the flow passages.
